UNITED STATES PATENT OFFICE.

GEORGE F. KONOLD, OF ASPINWALL, PENNSYLVANIA, ASSIGNOR TO
IRON CITY TOOL WORKS, LIMITED, OF PITTSBURG, PENNSYLVANIA,
A LIMITED COPARTNERSHIP UNDER THE LAWS OF PENNSYLVANIA.

DIE FOR MAKING MATTOCKS AND SIMILAR TOOLS.

No. 826,789.

Specification of Letters Patent.

Patented July 24, 1906.

Application filed December 23, 1904. Serial No. 238,119.

To all whom it may concern:

Be it known that I, GEORGE F. KONOLD, a resident of Aspinwall, in the county of Allegheny and State of Pennsylvania, have invented a new and useful Improvement in Dies for Making Mattocks and Similar Tools; and I do hereby declare the following to be a full, clear, and exact description thereof.

My invention relates to pressing-dies for the manufacture of mattocks and similar tools, its object being to provide dies of suitable construction for shaping and finishing the mattocks to standard and uniform shape.

To these ends my invention comprises, generally stated, a pair of dies, one of which has a longitudinal central rib with transversely-inclined face on each side thereof by which the mattock-blade may be spread laterally by separate pressing operations on each side of its central rib, this die being also preferably provided with a longitudinally-inclined face on its rear end in line with the transversely-inclined face adapted in connection with such spreading operations to develop a tapered face near the cutting edge of the mattock-blade.

It also consists in certain other improvements hereinafter more fully set forth and claimed.

To enable others skilled in the art to make and use my invention, I will describe the same more fully, referring to the accompanying drawings, in which—

Figure 1 is a side view of a press for use with the dies, as above described. Fig. 2 shows perspective views of the top and bottom dies for spreading the mattock-blades by means of transverse inclined faces on each side of the central rib. Fig. 3 is a side view of the dies of Fig. 2, showing the blank in position to be operated. Fig. 4 is a cross-section on the line 4-4, Fig. 3. Fig. 5 shows perspective views of the edge-pressing dies for finishing the eye and the edge of the mattock. Fig. 6 shows a blank suitable for the operation of the dies of Figs. 2 to 4. Fig. 7 shows the blank after a pressing operation of said dies; and Fig. 8 shows the finished mattock-blade after the operation of said dies and those of Fig. 5 and ready for trimming and grinding, the said blanks being shown in side and face views.

The press illustrated in Fig. 1 shows a press suitable for the dies involving the invention, such press providing for regular fixed pressing strokes as distinguished from the ordinary hammer strokes by which mattock-blades have heretofore been developed. In said press the housings are shown at 1, these housings carrying the anvil-block 2, on which are supported the dies and having the horizontal eccentric-shaft 3 mounted therein and carrying suitable eccentrics 4, operating with suitable eccentric-straps and pitman extensions 5 to give the regular reciprocating pressing stroke to the die-block 6, moving in guides 7 and carrying the top or moving die. The press may be driven by any suitable power. It is illustrated as driven by a motor 8 through suitable gearing 9. 70

The dies of Figs. 2, 3, and 4 are mounted in the anvil-block 2 and the reciprocating die-block 6, and I will first describe that construction and the functions performed by them. They are employed for the purpose of imparting the final shape to the mattock-blade after it has been properly developed by other pressing-dies, the mattock-blank having the fully-developed eye 10 and on one side thereof the blank 11, from which the cutter is to be developed, while on the other side is the mattock-blade 12, which has been partly developed by previous pressing operations, this blade having the central rib 13 and the rounded corner portions 14, while the eye portion at the junction of the mattock-blade and eye has been fully developed, as shown at 15. 75

The dies shown in Figs. 2 to 4 are employed for the purpose of imparting the final shape to the mattock-blade as so previously developed, while the dies shown in Fig. 5 are employed for the purpose of edging the blank and holding the eye central thereof and imparting uniform finish to the rounded corner portions and their junction with the eye. In the dies of Figs. 2 to 4 the top die 16 is an ordinary square die with a flat bottom face, while the lower die 17 is of peculiar shape. It has the longitudinal central rib 18 and on each side thereof the transverse inclined face 19, and extending down from each such inclined face the front corner of the die is beveled off to form the diagonal die-face 20. 90 95 100

to permit the blank to be so placed upon the die that the rounded corner 14 thereof may be placed upon the transversely-inclined or tapered face 19, the eye portion of the mattock 5 resting against the diagonal face 20 of the die. Such beveled corner or diagonal face 20 and the transversely-inclined face 19 are connected by the diagonal curved inclined portion 21, corresponding in shape to the metal at the 10 junction of the eye and blade of the mattock. Beyond each transverse inclined face 20 is the longitudinal inclined face 22, connected to the transversely-inclined face 20 along the diagonal line 23, such diagonal lines extending 15 backwardly to the central rib 18 near the rear of the die. The transversely-inclined faces 20 are also preferably inclined or tapered longitudinally according to the natural taper of the mattock-blade to be formed.

20 The dies 24 and 25 of Fig. 5 are of the same shape, each having near the forward end the V-shaped projection 26, with the curved face 27 in front of the same corresponding in shape to the desired finished shape of the forward 25 portion of the eye 10, while back of said V-shaped projection 26 is the curved face 28, corresponding to the desired curve of the rounded shoulder portion 30 of the finished mattock-blade, and beyond the same the inclined edging face 28, which flares slightly, according to the desired spread or increasing 30 width of the finished mattock-blade.

In the use of the dies above described a blank such as shown in Fig. 6 and above described having the fully-developed eye 10, the blade 12, with its central rib 13 and rounded corners 14, is placed upon the transversely-inclined die-face 19 of the lower die 17 on one side of the central rib 18, its eye 35 portion fitting against the diagonal face 20 at the corner of the die and over the diagonal curved inclined portion 21 thereof. Under pressure of the top die this side of the mattock-blade is then spread out, when the mattock is then placed in like position on the transversely-inclined die-face on the other side of the central rib to spread out in like 40 manner the other side of the mattock-blade. At the same time through the longitudinal inclined face 22 in line with each transverse inclined face 20 the inclined tapering face 31 of the blank is developed, partly by one such 45 pressing stroke on one side of the central rib and partly by the other pressing stroke on the other side of the central rib.

50 In the previous pressing of the blank shown in Fig. 6 and before it is subjected to the action of the dies of Figs. 2 to 4, or in the spreading of the blade by means of the dies of Figs. 60 2 to 4, the blade may be spread irregularly on one side or the other and the eye of the blank thus drawn out of central position, and to overcome this difficulty the blank is pressed between the dies of Fig. 5, which fin-

ish the rounded corner portions 30 and bring 65 the eye central of the blade, at the same time forcing the metal of the blade somewhat forward toward the point thereof and holding the blade to the desired finished shape, insuring a finished straight side edge 32. The 70 blade may thus be subjected alternately to the action of the dies of Figs. 2 to 4 on each side of the central rib 18 and then to the action of the dies of Fig. 5, being thus spread and drawn out longitudinally, while the 75 blank is held to proper shape and the eye maintained central of the blank, and the junction 33 of the eye and blade is brought to exact finished shape. In this way by as many pressing strokes as necessary the 80 blank is brought to finished shape, such as shown in Fig. 8, having in addition to the finished eye 10 rounded corner portions 30, a central rib 13, and tapering face 31 close to its cutting edge. The surplus metal may 85 then be cut from the blank to form its cutting edge and the blank be suitably ground and finished.

By means of the dies herein described I am 90 enabled from a blank which has been previously brought substantially to the shape shown in Fig. 6 to produce at the same heat the finished mattock, having wide mattock-blades of uniform shape and taper with properly-formed edges and having the eye central 95 of such blade by a few pressing strokes.

What I claim is—

1. In pressing-dies for the manufacture of mattocks and similar tools, the combination of a pair of dies, one of which has a flat working face, while the other has a central rib and a transversely-inclined face on each side thereof for drawing out the mattock-blade laterally.

2. In pressing-dies for the manufacture of mattocks and similar tools, the combination of a pair of dies, one of which has a central rib and a transversely-inclined face on each side thereof for drawing out the mattock-blade laterally, and a diagonal face at each corner to provide for placing the blade upon such transversely-inclined face.

3. In pressing-dies for the manufacture of mattocks and similar tools, the combination of a pair of dies, one of which has a flat working face, while the other has a central rib and a transversely-inclined face on each side thereof for drawing out the mattock-blade laterally, and a longitudinally-inclined face near the rear portion of the die in line with each transversely-inclined face for forming a tapered face near the cutting edge of the blade.

4. In pressing-dies for the manufacture of mattocks and similar tools, the combination of a pair of dies, one of which has a central rib and a transversely-inclined face on each side thereof for drawing out the mattock-

blade laterally, and a diagonal face at each corner to provide for placing the blade upon such transversely-inclined face, and a longitudinally-inclined face near the rear portion 5 of the die in line with each transversely-inclined face for forming a tapered face near the cutting edge of the blade.

In testimony whereof I, the said GEORGE F. KONOLD, have hereunto set my hand.

GEORGE F. KONOLD.
